INVENTOR

BY Victor J. Evans

ATTORNEY

John J. O.
WITNESS:

UNITED STATES PATENT OFFICE.

MELCHOIR ZUGERMAYER, OF EGG HARBOR CITY, NEW JERSEY.

COMBINATION TOOL.

Application filed March 19, 1924. Serial No. 700,846.

To all whom it may concern:

Be it known that I, MELCHOIR ZUGERMAYER, a citizen of the United States, residing at Egg Harbor City, in the county of 5 Atlantic and State of New Jersey, have invented new and useful Improvements in a Combination Tool, of which the following is a specification.

This invention relates to tools, and more 10 particularly to a combination household tool which is designed to provide in a compact form a plurality of tools which are used frequently about a house.

Another object of this invention is to provide 15 a combination tool as specified, the principal use for which is to raise window-sashes when it is difficult to raise them by ordinary means, as at such times when the window-sash sticks due to expansion of the 20 window-sash and frame under atmospheric conditions.

A further object of this invention is to provide 25 a tool as specified, which includes a relatively heavy structure body carrying a leverage head at one end and a removable hammer-head and screw-driver structure at the opposite end, which latter structure is held against accidental removal by a suitable set-screw and removable lug.

30 Other objects of the invention will appear in the following detail description, and in the accompanying drawings wherein:

Figure 1 is a side elevation of the improved tool,

Fig. 2 is a top plan of the improved tool.

Fig. 3 is a fragmentary bottom plan of the tool,

Fig. 4 is an end view of the tool showing the hammer and screw-driver end.

40 Fig. 5 is a cross-section through the tool taken on the lines 5—5 of Fig. 1 illustrating the adjustable fulcrum or support,

Fig. 6 is a detail cross-section through the modified form of tool, and

45 Fig. 7 is a detail view of a modified form of the fulcrum.

Referring more particularly to the drawings, the improved combination tool comprises a main cylindrical body 1 which has an integral or attached head 2 mounted on 50 one end thereof. The head 2 has its upper surface slightly concavely curved and its lower surface beveled flat so that it may rest in abutting engagement with a window-frame, with the relatively sharpened edge 3

engaged beneath the sash to permit the sash to be moved by a leverage action upon the pivoting of the tool upon its fulcrum 4. In the preferred form of the invention shown in Figs. 1 to 5, inclusive, the fulcrum 4 comprises a stand having a forked upper end, the arms of which are curved to clear the body 1. The arms 5 of the fulcrum 4 have trunnions 6 at their upper ends which extend inwardly and engage in longitudinally extending grooves 7 formed at diametrically opposed points in the body 1. If it is so desired, the head 2 may be provided with a notch 8 adjacent each side at its sharpened edge to permit the device to be used as a nail or tack puller, as well as for its primary purpose of raising window-sashes which become tightly wedged for various reasons.

The body 1 is provided with a longitudinal bore 10 at the end opposite to the end upon which the head 2 is mounted and this bore opens out through a slot 11. A screw-driver 12 is housed within the bore 10 and it has a lug 13 formed thereon which rides in the slot 11. The screw-driver 12 is prevented from passing completely out of the bore 10 by the engagement of the lug 13 against the body-encircling portion of the hammer 15. The hammer 15 is shown as a double-headed hammer, the heads 16 of which are connected by the body-encircling portion 17. A set-screw 18 threads through the hammer-head and through the body 1 for engagement with the screw-driver 12 to hold the screw-driver 90 telescopically within the body. By loosening the engagement of the set-screw and screw-driver, the latter may be extended out of the body for use.

In Fig. 6, a modified form of the invention 95 is shown in which the body 1 has longitudinally extending ribs 30 formed thereon at diametrically opposite points, which ribs have flat upper surfaces against which the trunnions 6 of the fulcrum 4 engage. In all other respects, the modified form is similar to the preferred form heretofore described. If it is so desired, the modified form of fulcrum as shown in Fig. 7, may be used in connection with the preferred or modified 100 construction of the body 1 in lieu of the fulcrum structure 4.

It is of course to be understood that the invention may be constructed in various 110 other manners and the parts associated in

different relations, and therefore I do not desire to be limited in any manner, except as set forth in the claims hereunto appended.

What I claim is:

- 5 1. A tool comprising a cylindrical body having a head at one end thereof, said head having its upper surface concavely curved and its under surface beveled for providing a substantially wedge-shaped outer end, and said head being provided with a notch extending inwardly from its wedge edge, said body having longitudinally extending grooves in its sides, a fulcrum including a

base and upstanding arms, said arms having trunnions formed upon their upper ends and 15 engaging slidably in said grooves.

2. A tool comprising a substantially cylindrical body having parallel longitudinal grooves therein, a head mounted on one end of said body and having its under surface 20 beveled to provide a flattened surface, and a fulcrum having trunnions thereon slidably engaging in said grooves.

In testimony whereof I affix my signature.

MELCHOIR ZUGERMAYER.
